Clayton and Son.

UNITED STATES PATENT OFFICE.

C. B. LOVELESS, OF SYRACUSE, NEW YORK.

IMPROVEMENT IN GRATES.

Specification forming part of Letters Patent No. 36,098, dated August 5, 1862.

To all whom it may concern:

Be it known that I, C. B. LOVELESS, of Syracuse, county of Onondaga, in the State of New York, have invented a new and useful Hot-Air Grate; and I do hereby declare that the following is a full, clear, and exact description thereof, reference being had to the accompanying drawings, and to the letters of reference marked thereon.

In the drawings, Figure 1 is a front elevation. Fig. 2 is a cross-vertical section.

To enable those skilled in the art to make and use my invention, I will describe its construction and operation.

A represents the front plate of the grate; B, the grate; C, the hollow cast-iron columns; D, the cast-iron hollow fire-back; E, the hollow cast-iron air-chamber over the grate and communicating with fire-back through pipes C; F, the hollow or chamber in the wall below the grate; G, the chimney-wall; I, the smoke-flue. *a a* are the cold-air registers at the bottom of the apparatus, one on each side of the grate. *b b* (shown in red lines, Fig. 1) are the cold-air passages from registers *a a* to the wall-chamber F, which is a continuation of the hollow of the fire-back D, both of them forming one chamber; *c*, the regulating-register for turning the heated air into or out of the room containing the grate; K, the air-pipe for conveying the heated air to an upper apartment; *e*, a damper-valve in pipe K; H, the fender.

In constructing my invention the pipes C, air-chamber E, and fire-back D are made of cast-iron and of a shape substantially that set forth in the drawings.

It will be seen in the drawings that the smoke-flue I is much contracted by building the brick back wall, G, quite near the pipes, air-chamber, and fire-back.

The brick wall below the grate is set somewhat forward of the fire-back D, so as to form a chamber between said wall and the lower rear part of the fire-back D.

In the operation of my invention the cold air (which is always nearest the floor) is received at the opened registers *a a*. Thence it passes through the passages *b b* into the chamber F, thence upward into the chamber of the fire-back D, thence through pipes C upward into the air-chamber E. The air in its passage through these pipes and chambers becomes heated by the action of the fire which is made in the grate B. The air thus heated is then discharged into the room through the register *c*, or, if wished, this register may be closed, damper *e* be opened, and the heated air be conveyed upward for the warming of a room on the second floor. When the registers *a a* are closed, the grate acts as an ordinary grate.

By this simple arrangement I am enabled to utilize the large amount of heat usually wasted in heating the fire-back, thus producing a cheap "hot-air grate" capable of a great saving in heat and fuel.

Having thus fully described my invention, what I claim as new, and desire to secure by Letters Patent, is—

The cold-air registers *a a*, chamber D, vertical pipes C, chamber E, and hot-air register *c*, in combination with the open fire-grate B, when constructed substantially as described.

In testimony that I claim the above I hereunto set my hand in presence of witnesses.

C. B. LOVELESS.
